FIG. 1 is a bottom left perspective view of an assisting device for opening door knobs and handles;
FIG. 2 is a bottom plan view thereof;
FIG. 3 is a top plan view thereof;
FIG. 4 is a front elevation view thereof;
FIG. 5 is a rear elevation view thereof;
FIG. 6 is a left side elevation view thereof; and,
FIG. 7 is a right side elevation view thereof.
The stippled shading shown in the figures represents texture.
The broken lines shown in the figures represent portions of
the assisting device for opening door knobs and handles that
form no part of the claimed design.
